Primary Examiner — Brian N Vinson(74) *Attorney, Agent, or Firm* — Perkins Coie LLP**CLAIM**

The ornamental design for an electronic pillar candle having a flame-shaped element illuminated from two sides thereof, as shown and described.

DESCRIPTION

FIG. 1 is an isometric view of the electronic pillar candle; FIG. 2 is a front view of the electronic pillar candle of FIG. 1; FIG. 3 is a rear view of the electronic pillar candle of FIG. 1; FIG. 4 is a left side view of the electronic pillar candle of FIG. 1;

FIG. 5 is a right side view of the electronic pillar candle of FIG. 1;

FIG. 6 is a top view of the electronic pillar candle of FIG. 1; illustrating the two light sources providing illumination to the flame-shaped element;

FIG. 7 is a bottom view of the electronic pillar candle of FIG. 1; and,

FIG. 8 is a cross-sectional view of the electronic pillar candle of FIG. 1; illustrating the two light sources providing illumination to the flame-shaped element.

The broken-line disclosure represents portions of the electronic pillar candle having a flame-shaped element illuminated from two sides thereof which form no part of the claimed design.
